UNITED STATES PATENT OFFICE.

JAMES M. ELLIS, OF NEW HAVEN, CONNECTICUT.

BUTTON.

SPECIFICATION forming part of Letters Patent No. 380,678, dated April 10, 1888.

Application filed September 3, 1887. Serial No. 248,745. (No model.)

To all whom it may concern:

Be it known that I, JAMES M. ELLIS, a citizen of the United States, residing at New Haven, in the county of New Haven, State 5 of Connecticut, have invented certain new and useful Improvements in Buttons, of which the following is a specification, reference being had therein to the accompanying drawings, in which—

10 Figure 1 is a transverse section of the button. Fig. 2 is a view of the cross-bars, made from a single piece of wire; and Fig. 3 is a plan view showing the bars in position.

My invention relates to a class of cheap buttons which are mostly used on pantaloons, though they are otherwise used—as, for example, in upholstery. This class of buttons are made of thin sheet-metal disks with central openings and with wire bars across the openings, whereby they are stitched to garments. The bars have been made in various forms. Straight wire bars across the openings have been used; also wire bars the ends of which have been bent in opposite directions, both styles 20 of bars forming buttons with two holes, and with no means for holding the thread with which the buttons are stitched to the garment in the center of the openings. Bars have also been made of a single piece of wire bent in the 25 form of the figure 8, the crossing of the bent wire being in the center of the opening, forming buttons with four holes not all alike. Blanks cut from woven wire which has been tinned or coated with an alloy by dipping the 30 woven wire in melted tin or in a melted alloy, whereby the intersections of the woven wire are soldered together, have been used, the blanks being so arranged that an intersection of the woven wire will be in the center of the 35 opening in the button, thus forming buttons with four equal holes, but with sharp knife-like edges formed by the cooling of the melted metal at the intersections of the woven wire as it is withdrawn from the "dip" or melted 40 metal, which cuts the thread as readily as a knife.

The object of my invention is to make this kind of button with a single piece of wire to form with the central opening four equal holes 50 in the button, and in such a manner that the thread will be held by the intersections of the wire in the center of the opening and be in contact with smooth metal surfaces.

To this end the invention consists in a piece of wire the end parts of which cross each other 55 at right angles and equal in length the diameter of a circle of which the central part is an arc, as is hereinafter more fully explained.

The front and back parts, *a* and *b*, of the button are punched from thin sheet metal in the 60 usual way, with central openings. The rims and form of the parts are also made in the usual and well-known way. The straight bars *m* and *n*, made from a single piece of wire, Fig. 2, the end parts of which cross each other 65 at right angles, the central part of which is curved to fit within the circular rim of the back part, *b*, of the button, are placed in the back part, as shown in Fig. 3. The wire is bent or wound around a former, the end parts, 70 *m* and *n*, equaling in length the diameter of a circle of which the curved part *x* is an arc. Then by dies the front part is closed over the back part, with the bars between the parts. By this construction the ends of the bars will 75 be equidistant from each other, their intersection will be in the center of the central openings, and a button with four equal holes and smooth wire bars, which will not cut the thread, is the result.

Coated woven wire is much more expensive than wire, and blanks cut from it are attended with waste. In wire cross-bars wound around a former there is no waste, and a cheaper and better button is the result.

Having described my improved button, what I claim as new, and desire to secure by Letters Patent, is—

The herein-described button, consisting of the front and back parts, combined with the 90 straight bars *m* and *n* in one piece with the curved part *x*, the length of the bars equaling the diameter of a circle of which the curved part *x* is an arc, the said bars arranged between the front and back parts of the button, and 95 crossing each other at right angles at the center of the openings in said parts, as shown and described.

In testimony whereof I affix my signature in presence of two witnesses.

JAMES M. ELLIS.

Witnesses:

GEORGE TERRY,
J. EDWD. LUDINGTON.
